UNITED STATES PATENT OFFICE.

HOWARD D. COLMAN, OF ROCKFORD, ILLINOIS, ASSIGNOR TO HOWARD D. COLMAN,
LUTHER L. MILLER, AND HARRY A. SEVERSON, COPARTNERS DOING BUSINESS
AS BARBER-COLMAN COMPANY, OF ROCKFORD, ILLINOIS.

TEXTILE APPARATUS.

1,304,661.

Specification of Letters Patent. Patented May 27, 1919.

Original application filed February 24, 1908, Serial No. 417,250. Divided and this application filed April 27, 1910, Serial No. 557,859. Renewed September 30, 1918. Serial No. 256,365.

To all whom it may concern:

Be it known that I, HOWARD D. COLMAN, a citizen of the United States, residing at Rockford, in the county of Winnebago and

5 State of Illinois, have invented certain new and useful Improvements in Textile Apparatus, of which the following is a specification.

This invention relates to an improved 10 means for presenting textile elements and loom elements, as, for example, warps, loom harnesses and loom reeds, to an operating mechanism. In the present embodiment the invention is illustrated as applied to a machine for drawing warp threads through harnesses and reeds.

The object of the invention, generally 20 stated, is to economize the time of textile machines, as for instance, warp-drawing machines. It is always desirable to make the output of a machine as large as possible, and this is especially true when the machine is expensive, as in the case of a warp-drawing machine. Obviously one method of increasing the output of a machine is to keep 25 it in operation as nearly continuously as possible.

A considerable amount of time is necessarily expended in arranging a warp, a set 30 of harnesses and a reed for presentation to a warp-drawing machine. During the intervals between its operation upon successive sets of elements, the machine, as heretofore arranged, has necessarily been idle, and it 35 is to dispense with this idle period of the machine that the present invention has been produced.

In the accompanying drawings, Figure 1 40 is a front elevation of a warp-drawing apparatus embodying my invention, portions being broken away to shorten the view. Fig. 2 is a side elevation of a truck for serving the warp-drawing machine, a loom beam and a warp carriage being represented as in 45 place on the truck. Fig. 3 is a detail view showing the warp carriage in another position. Fig. 3^a is a fragmental detail view of

an arm mounted on the truck. Fig. 4 is a side elevation of the truck and an end elevation of the warp-drawing machine, the machine and the truck being in operative relation to each other, and the warp being partly drawn in. Fig. 4^a is a fragmental top plan view of one of two distance members on the truck, and Fig. 4^b is a similar view of the 50 other distance member and a half-nut forming part of the means for moving the truck. Fig. 5 is a view similar to that of Fig. 4, but showing the warp as completely drawn in and the warp carriage and harness and 55 reed carriage as withdrawn from the mechanism. Fig. 6 represents the truck as removed from the warp-drawing machine, and the harness and reed carriage as having been placed temporarily upon certain supports 60 on the warp carriage. Fig. 7 is a sectional view through the harness and reed carriage and a part of the warp carriage, the reed and the harnesses also being shown in section. Fig. 8 is a fragmental view of the 65 harness and reed carriage. Fig. 9 is a fragmental view of the warp carriage with a drawn-in warp thereon. Fig. 10 illustrates a device adapted to be removably connected to the warp carriage. 75

The warp-drawing machine may be of any suitable construction. I have herein illustrated a machine substantially similar to the one illustrated in Patent No. 1,115,399, dated October 27, 1914, to which patent reference 80 may be had for a detailed description of the machine.

The warp-drawing machine herein shown 85 comprises a bed A supported upon legs A'. The drive shaft A² is rotatably mounted in suitable bearings upon the bed A, and has at its outer end a tight pulley A³ and a loose pulley A⁴. Driven from the shaft A² in a suitable manner is a rock shaft A¹⁰ aligned with and driving a screw-threaded shaft B' 90 for feeding the warp-supporting carriage.

At the rear side of the bed are two upwardly-extending arms A¹¹ which carry a fixed guide rail A¹² extending throughout

the length of the machine. Said rail supports the carriages for the harnesses and the reeds. In the upper edge of the rail A¹² is a groove A¹³, (Fig. 5), and in the lower edge of the rail is a rabbet or guideway A¹⁴.

The parts thus far described are similar to those shown in the said patent. The bed A of the present machine, however, has been made longer at the head end or receiving end of the machine, and the harness-carriage-supporting rail A¹² and the warp-carriage-supporting and feeding shaft B' have been correspondingly lengthened.

The operating mechanism is indicated diagrammatically at D in Fig. 1.

The warp-drawing machine comprises a plurality of carriages for warps and a plurality of carriages for harnesses and reeds, preferably two warp carriages and two harness and reed carriages being provided. Each harness and reed carriage may, if desired, be identical in construction with the one illustrated in the said patent and as herein shown. It comprises end frames C²⁰ (Fig. 7) and two upper connecting rods C⁴ C⁵, the harnesses being supported from said rods, as indicated in Figs 7 and 8. The harness and reed carriage is provided with rollers C' adapted to run in the groove A¹³ of the rail A¹² and other rollers C² adapted to run in the guideway A¹⁴ in said rail.

The warp carriages may be of any suitable form, as for instance, that illustrated in the before-mentioned patent, and as shown herein. Each of said carriages consists, in this instance, of a framework B having a warp clamp B³ (Fig. 3) at its upper edge and a warp clamp B⁴ at its lower edge. In order that the warp threads may be placed under tension after they have been secured in the clamps B³ and B⁴, the clamp B³ is pivoted to the framework B at B^a, and is swung away from the clamp B⁴ by means of links B⁵, a rock shaft B¹⁹ and hand levers B⁶, as indicated in Fig. 1 herein and as fully illustrated and described in said patent. Said hand levers have been omitted from Figs. 2 to 6. The carriage is arranged to be slidably supported upon the screw-threaded feed shaft B' and the rock shaft A¹⁰ by means of feet B^x, which feet are not screw-threaded. At the rear end of each warp carriage is a half nut B¹⁶ (Fig. 1) adapted to engage with the feed shaft B', said nut being arranged to be thrown into and out of engagement with the screw shaft in any suitable manner, as, for example, that illustrated and described in said patent.

While a warp is being operated upon by the mechanism D, the carriage containing the warp stands upon the screw shaft B' and the rock shaft A¹⁰, the carriage being supported in a substantially upright position by reason of the fact that the portion

C^x (Fig. 4) of said carriage rests against a stationary portion A^x upon the warp-drawing machine.

In the operation of the warp-drawing machine, the threads supported in a carriage B are drawn through the eyes of harnesses and the spaces of a reed supported in a harness and reed carriage C, said carriages traveling past the operating mechanism. A carriage B and a carriage C will be herein-after termed, for convenience, a set of carriages. For use in handling each set of carriages there is provided a truck 1 which may be of any suitable form. It is herein shown as comprising two sills 2 and two uprights or standards 3 rigidly connected together by means of bars 4 and pieces 5. The parts 2, 4, and 5 constitute a base, at the side of which the standards 3 are located. The base is mounted upon casters 6 so that it may be moved into and out of operative relation with the warp-drawing machine, and so that it may be traversed alongside said machine. The rear ends of the sills 2 have fixed thereto stops, alining devices or distance members 7 (Figs. 4 and 4^a) arranged to lie against a shaft 8 supported in the warp-drawing machine frame near the floor and extending longitudinally of said machine. Said shaft may be driven in any suitable way, as, for instance, by means of a belt 9 running over a pulley 10 on the shaft A² and a pulley 11 on a stub shaft 12, the latter shaft carrying a pinion 13 which meshes with a spur gear wheel 14 on the shaft 8. The shaft 8 is screw-threaded throughout the greater portion of its length.

Upon one of the sills 2 is pivoted an arm 15 carrying a half-nut 16 which is adapted to engage the screw-threaded shaft 8 for moving the truck 1 longitudinally of the warp-drawing machine. The arm 15 may have a rearward extension carrying a foot piece 17 for convenience in throwing the half-nut into and out of operative position.

Upon the forward side of the truck 1 is a bar 18 upon which is mounted a pair of posts 19 for supporting the journals of a loom beam a. These posts are omitted from Fig. 1. Preferably the posts 19 are adjustable in position to accommodate beams of different lengths. They are herein shown as slotted and as being clamped in adjusted position on the bar 18 by clamping bolts 20.

Two arms 21 and 22 are pivoted upon the uprights 3 to swing in a vertical plane. The arm 22 has a notch 23 (Fig. 3^a) in its outer end to receive a projection 24 upon one end of a warp carriage B. The other arm is also arranged to support one end of a warp carriage and is provided with suitable means for preventing undesired movement of the frame with relation to the arms 21

and 22. In this instance, an annular clamp 25 is provided upon the outer end of the arm 21 and within said clamp is mounted a disk 26 having a non-circular opening 27 5 therein to receive a correspondingly shaped projection 28 upon one end of the warp carriage. The annular clamp 25 may be tightened by means of a screw 29 to frictionally clamp the disk 26 so that while the 10 warp carriage may be turned by the operator it shall be held against gravitational movement.

The arms 21 and 22 are arranged to be swung by means of hand levers 30 pivoted 15 upon the uprights 3 and connected to said arms by means of links 31, said links having a pin and slot connection with the arms. 32 are pins for limiting the pivotal movement of the hand levers 30 in one direction. The 20 pivotal movement of said hand levers in the opposite direction is limited by the engagement of the links 31 with the pivotal supports of the hand levers, as shown in Fig. 2. The hand levers 30 are fixed upon 25 a rock shaft 33 (Fig. 1) so as to move together.

For holding the sheet of warp threads up 30 out of the way of the operator so that he may have access to the forward side of the warp-drawing machine, I provide a guide or cross bar 34 carried by arms 35 which are pivoted at 36 to the upper ends of the uprights 3. The arms 35 are extended below their pivots, and to these extended ends are 35 connected coiled tension springs 37 which tend to hold the cross bar in either of the two positions shown in Figs. 2 and 4. 38 is a stop pin for limiting pivotal movement of the arms 35 in one direction. The warp- 40 support or guide 34 35 has been omitted from Fig. 1 in the interest of clearness.

To prevent undesired rotation of the 45 loom beam *a*, suitable means may be provided, as, for example, a bar 39 arranged to be laid across a rod 40 fixed in the truck frame. See Fig. 2. One end of the bar 39 is bent into suitable form to contact the gear teeth upon the beam, and the other end of 50 said bar is adapted to be depressed by the foot of the operator to press the brake end of the bar against said teeth. When the brake is no longer needed the bar 39 is withdrawn.

Fixed upon the upper part of each warp 55 carriage *B* are two notched brackets 41 for supporting the harness and reed carriage, the latter having pins *C*²¹ (Figs. 6 and 8) adapted to rest upon said brackets, as will appear hereinafter.

60 A pair of curved fingers 42 (Figs. 5 and 10) are arranged to be removably connected with the upper end of each warp carriage. The connecting means may be of any suitable character; for example, the fingers

may have hooked or bent ends 43 to enter 65 sockets 44 on the upper bar of the warp carriage. Said fingers are of sufficient length to support the bars *C*⁴ *C*⁵ of a harness and reed carriage, as will appear more fully hereinafter.

70 One method of using the apparatus herein disclosed will now be described:

Fig. 2 shows a truck 1 with its parts in position for the commencement of the loading operation. The cross bar or guide 34 is 75 down, and the arms 21 22 are in their lowered position, with a warp carriage *B* in place on said arms, and in inverted position. A loom beam *a* having a new warp *b* thereon is placed upon the support 19, the free end of 80 the warp being held in a clamp of any common or preferred construction, such as an ordinary plush clamp *c*. The warp is then carried over the guide 34 and the clamp *B*⁴ of the warp carriage *B*, as shown in Fig. 2. 85 After carrying the warp over the clamp *B*⁴, the operator prevents the warp beam from revolving by means of the foot brake lever 39 while pulling the warp into a smooth even sheet, the threads slipping through the 90 plush clamp *c* as tension is placed upon them. The warp is then secured in the clamp *B*⁴, and the warp carriage *B* rotated upon its supports in the arms 21 and 22 in the direction indicated by the arrow in Fig. 95 2, until the carriage reaches the position shown in Fig. 3. The upper warp clamp *B*³ is thus brought beneath the sheet of warp threads. The warp having been inserted in the clamp *B*³ and said clamp closed, the portion of the sheet extending between the clamps *B*³ and *B*⁴ is stretched or tensioned by means of one of the hand levers *B*⁶ as 100 explained in the patent hereinbefore referred to. The warp support 34 may then 105 be swung up into its operative position. The warp carriage is now ready to be placed upon its supports in the warp-drawing machine, but before that is done a harness and reed carriage *C* containing harnesses and a 110 reed is placed upon the head end of the rail *A*¹² and moved into operative relation with the mechanism *D*, the sides of the eye-spacer mechanism having been separated to admit the carriage *C*, as described in the before-mentioned patent. In placing the warp carriage *B* on the warp-drawing machine, the operator raises one of the hand levers 30 115 into the position shown in Fig. 5, thereby raising the warp carriage to the height indicated in said figure. The truck is then pushed up to the warp-drawing machine and the hand lever lowered into the position shown in dotted lines in Fig. 4, thereby lowering the warp carriage *B* onto its supports in the machine, the warp carriage *B* then being nearly opposite or in front of the harness and reed carriage *C*. The warp car- 120 125

riage B being arranged to be sensitively fed by the shaft B', it is necessary to disconnect the truck 1 from the warp carriage, which is accomplished by lifting the projection 24 out of the notch 23 in the arm 22 and drawing the projection 28 out of the opening 27. The arms 21 and 22 are thereupon swung up out of the way, as shown in full lines in Fig. 4. The lateral tension or deflection is put upon the threads as described in the before-mentioned patent, the warp carriage is advanced by the operator until the first warp thread is near the selector, the half-nut 16 on the truck is thrown into engagement with the screw shaft 8, and the half-nut B¹⁶ on the warp carriage is placed in engagement with the screw shaft B'. The warp-drawing machine being placed in operation, the harness and reed carriage C and the warp carriage B are fed past the operating mechanism, and the truck 1 is moved along the front of the machine by means of the screw threaded shaft 8 engaging the half-nut 16.

25 While the machine is operating upon the warp, harnesses and reed contained in the set of carriages just referred to, another set of carriages B and C is loaded. When the first warp has been drawn in, the machine stops. The operator then opens up the eye-spacer mechanism, disengages the half-nut 16 from the feed shaft 8, and pushes the harness and reed carriage and the warp carriage forward along the machine until said carriages are clear of the operating mechanism D, the operator steadyng the warp carriage after the latter has passed the ledge A^x. The operator then lowers the arms 21 and 22 and engages said arms with the projections 24 and 28 on the warp carriage; lowers the clamp B³ by means of one of the hand levers B⁶; places the hooks 42 in the sockets 44 and swings said hooks under the top bar C⁵ of the carriage C; operates the hand lever 30 to withdraw the warp carriage and the harness and reed carriage from the warp-drawing machine, as shown in Fig. 5, and then rolls the truck, bearing the drawn-in warp, the harness and reed carriage and the warp carriage, away from the warp-drawing machine. The operator then places the second set of carriages and the second truck in operative relation to the machine, and sets the latter in operation. The first harness and reed carriage is then lifted off the fingers 42 and suspended on the supports 41 on the warp carriage, so as to provide slack in the threads between the clamp B³ on the one hand and the harnesses and the reed on the other, and to bring the harness eyes into approximately a plane with the clamp B³, as shown in Fig. 7. The thread ends projecting through the reed are then drawn up and tied in small bunches, the fact that the harness eyes are approximately

in a plane with the warp clamp B³ enabling the operator to draw the threads up to substantially the same length. The clamp B³ may now be opened to release the warp. The carriage C is next removed from the harnesses and the reed, leaving the harnesses and the reed hanging on the warp; the warp carriage is lowered by means of one of the hand levers 30 into its lowest position; the beam is revolved to draw the harnesses and the reed up to the guide 34; and then while continuing to revolve the beam the operator swings the guide 34 down into inoperative position, the rotation of the beam keeping the warp taut so that the threads shall be wound parallel on the beam; the harness and the reed are laid on the beam and tied to it; and the beam removed from the truck. The first truck is now ready to be used in placing another warp in the warp carriage on said truck.

It will be seen that while the machine is operating upon the second warp, the operator is getting the drawn-in warp ready to be sent to the weave room, and is preparing a third warp and third set of harnesses and reed for reception in the warp-drawing machine. The machine may be kept in operation substantially all of the time, thereby greatly increasing its output.

It will be understood that while I have described the apparatus as embodied in a warp-drawing system, the broad features thereof are applicable to a warp-tying apparatus. It will also be understood that the invention herein described is applicable to warp-drawing machines of other forms than that herein alluded to, and that various changes may be made in the truck and associated apparatus without departing from the spirit of the invention.

This application is a division of application Serial No. 417,250, filed February 24, 1908.

I claim as my invention:

1. The combination, with a warp-drawing machine having a carriage-feeding element and a warp carriage adapted to removably engage said feeding element, of a truck having pivoted arms arranged to engage said carriage; and means for moving said arms to move the carriage with relation to the feeding element.

2. The combination, with a warp-drawing machine having a carriage-feeding shaft, a carriage-supporting member, and a warp carriage adapted to rest upon and engage said shaft and lean against said member, of a truck having arms engageable with said carriage; and means for pivotally moving said arms to move the carriage with relation to said shaft and member.

3. In a transfer device for transferring the work with relation to a warp-drawing machine, the combination, with a transfer

- truck, of upright warp beam supports thereon, and pivoted harness transfer supports carried by said truck.
4. The combination, with a warp-drawing machine having harness-supporting means, of a movable transfer device having harness supports, said supports being adapted to be brought into coöperative relation to the supporting means on the machine to permit the transference of the harness from the machine to the transfer device, and means for alining said transfer device into the required relation with said machine prior to such transference.
- 10 5. The combination, with a warp-supporting frame comprising two parallel clamps, of means for supporting the frame for rotation upon an axis extending parallel with and between the clamps.
- 20 6. The combination of means for supporting a warp beam, a warp-supporting frame comprising two parallel clamps, and means for supporting the frame for rotation upon an axis extending between the clamps and parallel with the clamps and the beam.
- 25 7. The combination, with a warp-drawing machine having a carriage-feeding element and a warp carriage adapted to removably engage said element, of a truck having means to support a loom beam and means to support said carriage.
- 30 8. The combination, with a warp-drawing machine having a removable warp carriage, of a beam truck having means for removing the carriage from the machine.
- 35 9. The combination, with a warp-drawing machine having a removable warp carriage, of a beam truck having means for placing the carriage upon and removing it from the machine.
- 40 10. The combination, with a warp-drawing machine having a removable harness carriage, of means for removing the carriage from the machine.
- 45 11. The combination of a warp-drawing machine having a movably mounted warp carriage, said carriage having a clamp for supporting warp threads, and means on said carriage for supporting harnesses through which the threads have been drawn, the threads extending from the clamp and through the harnesses.
- 50 12. A warp-drawing machine having, in combination, a main frame, a warp carriage and a harness carriage both movably mounted on said frame and means on one of said carriages for supporting the other.
- 55 13. The combination, with a warp-drawing machine, of a truck adapted to be placed alongside the warp-drawing machine and comprising a wheeled base, two standards located one at each side of the base, and a work-supporting arm pivoted to each standard and adapted to extend toward the warp-drawing machine.
14. A truck arranged to serve a machine for operating upon warps, said truck having means to rotatably support a warp beam, arms pivoted on said truck, and a cross-bar supported by said arms for holding the threads elevated between the beam and the machine, said arms being arranged to swing to carry the cross-bar down and toward the beam.
15. A truck adapted to serve a machine for operating upon warps, said truck having means thereon for releasably clamping the warp carriage of such a machine.
16. A truck arranged to serve a machine for operating upon warps, said truck having means thereon for releasably clamping the warp carriage of such a machine, and means for raising and lowering said clamping means.
17. A truck arranged to serve a machine for operating upon warps, said truck having swinging means thereon for supporting the warp carriage of such a machine, said means being adapted to releasably clamp the carriage.
18. A truck arranged to serve a machine for operating upon warps, said truck having thereon two pivoted arms adapted to support the warp carriage of such a machine and means on one of said arms for releasably clamping the carriage.
19. A truck arranged to serve a machine for operating upon warps, warp-carriage-supporting members pivotally supported on said truck, means on one of said arms for releasably clamping the carriage, a hand lever, and a link connection between said hand lever and said carriage-supporting members.
20. The combination of a supporting structure, two warp-frame-supporting arms pivoted to said structure, a hand lever, two links connected to said hand lever, and a lost-motion connection between each link and one of said arms.
21. A truck arranged to serve a machine for operating upon warps, said truck having at one side a support for a loom beam, and at its opposite side a support for a warp frame, and intermediate said supports a support for the sheet of warp threads extending between the beam and the warp frame, said last mentioned support being withdrawable out of operative position.
22. The combination, in a warp-drawing apparatus, of a drawing-in mechanism; a frame for supporting a warp; a frame for supporting a harness; means on one of said frames for engaging the other frame; and means for removing the frame carrying said engaging means, to remove both frames from operative relation to the mechanism.
23. In a warp-drawing machine, a removable warp carriage, a removable harness carriage, and means on one of said carriages to engage and support the other carriage.

24. In a warp-drawing machine, a removable warp carriage, a removable harness carriage, and harness-carriage-supporting fingers removably connected to said warp carriage.
25. The combination, with a warp-drawing machine having a removable frame to contain some of the elements to be operated upon, of a truck movable toward and away from the warp-drawing machine, said truck having means thereon for engaging said frame; and means for operating said engaging means to remove said frame from the machine and for returning it thereto.
26. A truck arranged to serve a machine for drawing in warps, said truck having a support for a loom beam, means at one side of the truck for supporting loom harness, means intermediate the beam support and the harness support for supporting a sheet of threads extending between the beam and the harness, and truck-positioning means located on the same side of the truck as the harness-support.
27. An apparatus for facilitating the drawing of warps through loom harness, consisting of a truck having means to support a warp-beam, and harness-supporting members carried at one side of the truck and insertible into a warp-drawing machine to receive the harness.
28. An apparatus for facilitating the drawing of warps through loom harness, consisting of a truck having truck-positioning means at one side, and harness-supporting means at the same side and insertible into a warp-drawing machine to receive the harness.
29. In a warp-drawing apparatus, the combination with a warp-drawing machine comprising drawing means, a warp support, and loom-harness supporting means, of a truck having means to support the loom-harness, said last mentioned means being laterally insertible into the machine.
30. The combination, with a warp-drawing machine having harness supporting devices, of a movable transfer device having movable harness supports for holding one or more harnesses, said supports being adapted to be brought into co-operative relation to the supporting devices on the machine to permit the transference of the harnesses from the machine to the transfer device.
31. The combination, with a warp-drawing machine having supporting devices for loom elements, of a transfer device having means for supporting loom elements thereon, said supporting means being adapted to be brought into co-operative relation with the supporting devices on the warp-drawing machine to permit the transference of said loom elements from the machine to the transfer device, and means for alining said transfer device into the required relation with said machine prior to said transference.
32. The combination, with a warp drawing machine having means for supporting a plurality of harnesses in parallel, separated arrangement thereon, of an unloading device comprising a movable support and one or more hanger arms for holding in predetermined relation a plurality of harnesses, said device being adapted to be brought into co-operative relation with said machine to transfer the harnesses from the machine to said device.
33. The combination with a warp drawing machine having means for supporting a plurality of harnesses and a reed thereon in a generally parallel but separated arrangement, of an unloading device comprising a movable support, and means thereon for holding the harnesses and reed, said device being adapted to be brought into co-operative relation with said warp drawing machine to permit the transference of said harnesses and reed from the machine to the unloading device.
34. The combination, with a warp-drawing machine, of a portable loading or unloading device having means for supporting the removable loom elements of said warp-drawing machine, said supporting means including a warp beam support adjustable to accommodate warp beams of different lengths.
35. A truck arranged to serve a machine for drawing warp threads through loom elements, said truck having a support for a loom beam, and a bar to support a sheet of drawn-in warp threads intermediate the beam and the loom elements, said bar being withdrawable out of operative position.
36. In a transfer device for transferring the work with relation to a warp drawing machine, the combination, with a transfer truck, of harness supporting means comprising a pair of transfer arms, and means supporting said arms for swinging movement upon the truck to permit their withdrawal from the warp-drawing machine.
37. The combination, with a warp drawing machine, of a transfer device for transferring the work relatively to the warp-drawing machine, the said transfer device having a warp beam holder and collapsible harness supporting devices at the ends of said holder.
38. In a transfer device for a warp-drawing machine, the combination of a supporting frame for carrying the warp beam, and collapsible harness supports exclusively at the ends thereof, said supports leaving an intermediate unobstructed space.
39. In a transfer device for transferring the work with relation to a warp-drawing machine, the combination, with upright sup-

ports, of swingingly mounted harness-carrying and transfer arms thereon, said arms projecting at one side of said upright supports.

5 40. A truck for serving a warp-drawing machine, comprising a base, wheels for supporting the base, two standards located one

at each side of the base, and a work-supporting arm pivoted to each standard.

HOWARD D. COLMAN.
